UNITED STATES PATENT OFFICE.

CHARLES R. KLINE, OF READING, PENNSYLVANIA.

FURNACE AND BOILER CASING.

Application filed August 24, 1921. Serial No. 495,043.

To all whom it may concern:

Be it known that I, CHARLES R. KLINE, a citizen of the United States, residing at Reading, county of Berks, State of Pennsylvania, have invented a new and useful Furnace and Boiler Casing, of which the following is a specification.

My invention consists of a novel construction of a casing for furnaces, vapor, water, steam and other boilers, and comprises an outer casing of metal sheets built in sections whose meeting edges are locked in a novel manner, said sheets having an internal lining of asbestos or other suitable heat resisting material, which entirely encloses the boiler, said casing having openings aligning with insulated boiler or furnace doors and ensuring a dead air space between the actual surface of the boiler and the outer casing, thereby insuring perfect insulation and a marked saving in fuel consumed.

It further consists of other novel features of construction, all as will be hereinafter fully set forth.

For the purpose of illustrating my invention, I have shown in the accompanying drawings a form thereof which is at present preferred by me, since it will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a vertical sectional view of a furnace and boiler casing embodying my invention.

Figure 2 represents on an enlarged scale a sectional view of the right-hand portion of Figure 1.

Figure 3 represents a front elevation of Figure 2.

In carrying out my invention I provide an outer sectional casing composed of the front 2, the top 4, and rear and end walls, the casing sections being of metal or in the form of metal sheets as sheet-iron and provided with an internal lining 5 of asbestos or other suitable heat resisting materials whereby a sectional casing is provided which entirely encloses the boiler or the like, whereby a dead air space is insured between the surface of the boiler and the outer casing, thereby insuring perfect insulation and a

marked saving in fuel consumption. The juxtaposed meeting ends of the sections as seen at the top of Figure 1 are provided with flanges deflected therefrom at a right angle and provided with locking members composed of the body portion 13 and the inwardly converging walls 14.

In Figures 1 and 2, I have shown the boiler 19 as provided with the nonconducting covering 20 and with the front water leg 21 having the firing opening 22, which is accessible through the firing door 23, it being apparent that the latter is interiorly lined with non-conducting material, as indicated at 23*, and that the outwardly projecting flange 22*, which surrounds the firing opening 22, projects outwardly to such an extent that it is embedded in the lining 23* when the firing door is closed, so that a tight joint is effected when said door is closed. The casing front 2 has an opening 24, which is formed by an inturned casing flange 24 and is closed by the casing door 25, which is provided with the nonconducting lining 26. It will be further apparent that said casing door 25 is enough larger than the casing aperture 22 to provide, when closed, a margin of insulating material shutting tightly on the outside or face of the casing thus interposing a strip of insulation between the metal of the casing door and the metal of the casing thereby destroying the heat conductivity of the metals, it being apparent that said casing door is held in closed position by the handle 27, it being apparent that I have provided my novel casing with a door 25, in alignment with the firing door 23 of the boiler, and that said casing door when closed effectively seals the casing opening formed by the internal flange 24.

It will be apparent from Figures 1 and 2 that by providing the outer casing of metal built up in sections having the lining of asbestos or other suitable heat resisting material, which entirely incloses the boiler, and by providing the sectional casing with insulated doors, as 25 and 23, I insure a dead air space between the actual surface of the boiler and the outer casing, together with perfect insulation and a marked saving in fuel, it being apparent that when the door 25 with its inner insulated lining is closed, that the same forms in effect a continuation of the casing and the lining 5.

It will now be apparent that I have devised a novel and useful casing for a furnace

and steam, vapor and water boiler which embodies the features of advantage enumerated as desirable in the statement of the invention and the above description, and while 5 I have, in the present instance, shown and described a preferred embodiment thereof which will give in practice satisfactory and reliable results, it is to be understood that the same is susceptible of modification in 10 various particulars without departing from the spirit or scope of the invention or sacrificing any of its advantages.

Having thus described my invention, what 15 I claim as new and desire to secure by Letters Patent, is:—

1. In a device of the character stated, a casing for boilers, furnaces and the like composed of metal sheets lined on their interior with non-conducting material, a boiler 20 in said casing having a door, a door opening in said outer casing sheet aligning with said boiler door, and a casing door closing said opening and hinged to said outer sheet, the inner surface of said casing door being provided with a lining of non-conducting material and the inner surface of said boiler door being also provided with a lining of 25 non-conducting material, and an outer projecting member surrounding the opening 30 into said boiler, said member being adapted

to be embedded in the non-conducting material of said boiler door when the door is closed.

2. In a device of the character stated, a casing for boilers or furnaces composed of 35 metal sheets interiorly lined with non-conducting material, a door opening in one of said casing sheets formed by a deflected flange of said casing, a casing door hinged to said sheet in proximity to said opening, a lining of non-conducting material on the inner surface of said casing door, said casing door being larger than the casing aperture so as to provide when closed a margin of insulating material abutting tightly on 40 the face of said casing, thus interposing a strip of insulating material between the metal of the casing door and the metal of the casing, a door opening for a door within said door, a flange secured to said latter door opening and having a laterally projecting portion, and non-conducting material attached to the inner face of the inner door and adapted to be embedded in said flange 50 when the inner door is closed.

CHARLES R. KLINE.
